CLAIM

We claim the ornamental design for a microwave, as shown
and described.

DESCRIPTION

FIG. 1 is a perspective view of a microwave;
FIG. 2 is a front elevational view thereof;
FIG. 3 is a rear side elevational view thereof;
FIG. 4 is a right side elevational view thereof;
FIG. 5 is a left elevational view thereof;
FIG. 6 is a top plan view thereof; and,
FIG. 7 is a bottom plan view thereof.
The broken lines are shown for the purpose of illustrating
parts of the article that form no part of the claim.

(Continued)

The Thermador logo in the drawings, forming no part of the claimed design, is a registered trademark of the BHS Home Appliances Corporation.
